UNITED STATES PATENT OFFICE.

GEORGE A. ELLIS, OF DETROIT, MICHIGAN, ASSIGNOR TO THE AUTOMATIC CIGAR SELLER COMPANY, OF SAME PLACE.

COIN-CONTROLLED VENDING DEVICE.

SPECIFICATION forming part of Letters Patent No. 437,584, dated September 30, 1890.

Application filed February 25, 1890. Serial No. 341,722. (No model.)

To all whom it may concern:

Be it known that I, GEORGE A. ELLIS, of Detroit, in the county of Wayne and State of Michigan, have invented a new and useful Improvement in Coin-Controlled Vending Devices, of which the following is a specification.

My invention consists in an improvement in coin-controlled vending devices hereinabove fully described and claimed.

Figures 1, 2, and 3 are side elevations of the actuating mechanism in different positions with the box in vertical section. Fig. 4 is a detail of the connecting mechanism.

A represents the frame of the box, of any suitable size, shape, or material, for the use to which it is to be put.

A' represents a plate fastened to one side of the box, as shown in the figures, and projecting within the box to carry the operating mechanism.

The particular arrangement of slide for delivering the article to be sold is omitted in the drawings, because that usually varies with the size and shape of the article, and because there are many ways of connecting the delivery apparatus proper with its actuating mechanism.

C (indicated in dotted lines in Fig. 1) indicates the coin-chute, the lower end of which terminates so as to deliver the coin into the funnel-shaped receiver C², whose lower end is open.

G represents a shaft pivoted in plate A', on which is fastened an upwardly-extending arm g'. Shaft G extends through plate A', and is connected on the other side of said plate with the delivery apparatus indicated by lever g. (Shown in dotted lines in Fig. 1.)

D represents a lever, which is pivoted to the upper end of arm g', and carries on one end a counter-weight d, sufficient to normally depress that arm of lever D to which it is connected, but so proportioned as to be raised by the weight of a coin resting on the other and longer arm of lever D.

d⁴ represents a keeper secured on plate A' and extending over the long arm of lever D to guide the lever in its vibrations and limit the upward movement of the long arm of the

lever. This may be omitted and its office performed by a keeper d³, which is secured to plate A'.

d' represents a pin projecting from the side of the long arm of lever D and lying directly under the coin-receiver C² when the parts are in the position shown in Fig. 1.

d² represents a hook formed in the long arm of lever D near its end.

g² represents a shoulder formed in the lower part of arm g', and F represents a pawl pivoted to plate A', so that its upper end will engage with shoulder g² when the arm g' is swung to the right, as shown in Fig. 3.

F' represents a light spring, which holds the pawl F up to its work.

B' represents a bar sliding in an aperture in the box and in a keeper secured to plate A', having its outer end provided with a knob B for the hand of the operator.

b' represents a hook formed in the upper side of bar B', adapted to engage with hook d² on lever D.

B² represents a spring, which draws the bar B' toward the left, as shown in the figures, and which restores said bar to its normal position after it has been drawn out.

The bar B' is made of such length that when it is pushed into the box its inner end holds the pawl F out of engagement with the shoulder g² on arm g', and the spring B² is made stronger than the spring F' for this purpose.

The operation of my invention is as follows: When the apparatus is ready to receive a coin, the parts lie in the position shown in Fig. 1, in which it will be noticed that the bar B' is entirely disconnected from all other parts of the apparatus and may be operated freely without affecting any of the delivery parts of the machine. When a coin of the proper size and weight is dropped into the chute, it falls into the receiver C² and comes in contact with pin d', thereby depressing the long end of the lever D and causing the hook d² on said lever to lie in front of the hook b' on the bar B'. When the bar B' is now drawn out, the hooks d² and b' lock together, thus locking the lever to bar B', which carries with it the lever D, and this swings the arm g' and

rotates the shaft G, which is connected with and operates the delivery apparatus. As soon as the pin d' passes from under the coin which has been resting on said pin the coin drops into the money-box below. When the bar B' is fully drawn out to operate the delivery apparatus, the pawl F engages with the shoulder g² on arm g', and thus holds the shaft G against return to its normal position until the bar B' is forced in far enough to push the pawl F away from the shoulder g². As soon as the bar B' is moved toward the hooks d², b' disengages weight d and immediately restores the lever D and the parts connected therewith to their normal position, thus disconnecting the delivery apparatus entirely from the bar B'. This obviates the defect in certain machines of this character by which a dishonest person is enabled to obtain more than he has paid for through operating the actuating-bar through less than its whole range of movement, for it is evident that until the bar B' is fully returned home the machine will not be set to deliver another article, and that a slight inward motion of bar B' disengages it from lever D.

What I claim as my invention, and desire to secure by Letters Patent, is—

1. In a coin-controlled vending apparatus, the combination, with a vibrating counterweighted lever connected with the delivery apparatus, having a projection in the path of the descending coin, of an actuating-bar normally disconnected from said lever, and a

pawl for locking the delivery-actuating mechanism lying in the path of the actuating-bar, substantially as shown and described. 35

2. In a coin-controlled vending apparatus, a counterweighted lever D, connected with the delivery apparatus, having on its long arm 40 a projecting pin lying across the path of the descending coin, and a hook, a movable bar B', having thereon a hook b', and a pawl F, lying in the path of the bar B', substantially as shown and described. 45

3. In a coin-controlled vending apparatus, a movable bar having thereon a hook, a pivoted vibrating lever normally free from engagement with said bar and having thereon a hook to engage with the hook in the bar, 50 and a projection in the line of the coin-chute, whereby the actuating mechanism is connected by the weight of the coin.

4. In a coin-controlled vending apparatus, the combination of a lever pivoted to the delivery apparatus, having its short arm counterweighted and its long arm extending under the coin-chute and provided with a hook, with a movable bar having thereon a hook normally free from engagement with the lever-hook and engaged therewith when the hooked part of said lever is depressed by a coin, substantially as shown and described. 55 60
